UNITED STATES PATENT OFFICE

CHESTER J. O'BRIEN, OF CHICAGO, ILLINOIS, ASSIGNOR, BY MESNE ASSIGNMENTS, TO CALUMET STEEL COMPANY, OF CHICAGO, ILLINOIS, A CORPORATION OF DELAWARE

COLLAPSIBLE STRUCTURAL UNIT

Application filed March 4, 1931. Serial No. 530,036.

My invention relates to a collapsible structural unit and is concerned primarily with devices of this type which are utilized as reinforcing and supporting members in concrete constructions.

5 One object of my invention is to devise a structural unit composed of parts which reinforce the shearing and diagonal tensile strength of the beam or joist with which used and which may be properly spaced at the place of manufacture according to the design of the beam, or generally the place where used, and maintained in this spaced relation until used, the arrangement of the several 10 parts being such as to permit a collapsing of the unit to assume a substantially folded or overlapping condition to facilitate shipping and handling.

A further object is to provide a unit of the 20 character indicated which is so constructed and arranged as to eliminate any necessity for welding or other rigid types of securing of the principal reinforcing and spacing members, requiring only a simple connection of the parts which may be readily disassembled whenever desired.

A further object is to provide a collapsible 30 structural unit composed of reinforcing elements of the so-called stirrup type in which the spacing bars therefor have a loose connection with the stirrups and are themselves maintained in predetermined positions in order to facilitate collapsing, the lower bar being held above the bottom of the unit to 35 permit the ready insertion of the tension beam bars when the unit is placed in a form, and the upper bar being adapted to provide a support for the cross bars which reinforce the slabs in the monolithic type of construction.

40 These and further objects of my invention will be set forth in the following specification, reference being had to the accompanying drawings, and the novel means by which said objects are effectuated will be definitely pointed out in the claims.

In the drawings:

Figure 1 is a section of a concrete floor construction of the monolithic type, my 45 improved structural unit being shown as em-

bedded in the beam or joist portion of the floor.

Fig. 2 is a section along the line 2-2 in Fig. 1, looking in the direction of the arrows.

Fig. 3 is an enlarged end view of my improved structural unit, as it appears in Fig. 1.

Fig. 4 is a side view of the unit looking in the direction of the arrow 4 in Fig. 3.

Fig. 5 is an enlarged section along the line 5-5 in Fig. 3, looking in the direction of the arrows, and showing the manner of connecting the spacing bars and stirrups of the unit.

Fig. 6 is an enlarged view of the unit when occupying a collapsed position, the unit being viewed in the direction of the arrow 6 in Fig. 4.

Fig. 7 is a view corresponding to Fig. 3, but showing a modified form of unit, the particular difference residing in the manner 70 of vertically supporting the spacing bars in any given position.

Fig. 8 is a side view of the unit shown in Fig. 7, looking in the direction of the arrow 8 in said figure.

Fig. 9 is an end view of another modified form of the unit showing still another way 75 of vertically supporting the spacing bars.

Referring to Figs. 3, 4 and 5, the numeral 10 designates the intermediate stirrup members of the unit which are formed of bars having a predetermined diameter and shaped generally into the form of a U having laterally extending portions 11 at the ends of each limb for the purpose of providing a satisfactory bond with the concrete. It is important in units of this character to space the stirrups 10 according to a scheme dependent upon the design and lading of the beam and it is further desirable to accomplish this spacing by an arrangement which may not only be positioned at the place of manufacture, but will also insure the maintenance of this spacing during subsequent handling until the unit is placed in the form prior 85 to the pouring of the concrete. The instrumentalities by which these several results are accomplished will now be described.

In addition to the intermediate stirrups 10, the unit also comprises end stirrups 12 90

which are generally similar to the stirrups 10, but whose vertical limbs extend downwardly below the lower ends of said stirrups and are reversely bent to provide feet 13 which rest and provide a support on the bottom of the form, as hereinafter described, and the feet of each end stirrup 12 is connected by a horizontally extending portion 14 which is located substantially in the same plane as the similar portions 15 of each intermediate stirrup 10. One limb of each stirrup 12 on the same side of the unit receives a short sleeve 16, generally formed of simple steel tubing which is slipped down said limb prior to the forming of the bonding hook 11, and is moved downwardly along said limb until the curvature of the foot 13 prevents further movement. A spacing bar 17, preferably of channel section, is then rested on the upper ends of the sleeves 12 against the inner side of the indicated limbs of the end stirrups 12 and is then secured in the position just mentioned by means of a plurality of tabs 18 which are cut in the web of the bar 17 and bent laterally therefrom to embrace the adjacent limb portions of the end and intermediate stirrups. Prior to being so positioned, it will be understood that the tabs 18 will have been so located as to determine the spacing of the several stirrups in the unit from each other, dependent upon the design of the beam, and that when the several tabs are bent around the limbs of the stirrups, the nature of the connection is such that the several limbs may rotate within the tabs for a purpose herein-after explained.

A second sleeve or length of tubing 19 is then slipped over the indicated limb of each end stirrup 12, after which a second spacing bar 20 is rested thereon and connected to the several stirrups of the unit in the manner above described. On one side of the unit, therefore, there will thus be located spacing bars 17 and 20 which determine the relation of the stirrups of the unit to each other, as well as permitting the collapsing of the unit as hereinafter described, the spacing bars being further definitely fixed with relation to each other by the sleeves 16 and 19. On the opposite side of the unit a third spacing bar 21 may be positioned in the manner above described, so far as the employment of the tabs 18 is concerned, and utilizing sleeves 30 which are slipped over the vertical limbs of the end stirrups in the indicated side of the unit, the lower ends of said sleeves lying substantially in the same plane as the corresponding ends of the sleeves 12. The precise vertical position of the bar 21 is of slight importance, although it is usually placed so as to better facilitate the collapsing of the unit.

Figs. 3 and 4 illustrate the position assumed by the unit when it is placed in a form

prior to the pouring of the concrete, but this position is not suitable for shipment owing to its requirement for excessive space and difficulty of handling. The unit is accordingly collapsed into the position shown in Fig. 6, in which the stirrups of the unit are folded over into overlapping position with respect to each other. The achievement of this condition is, of course, made possible by the relation between the spacing bars and the stirrups, as well as by the fact that the spacing bars are maintained in fixed relation with respect to each other, so that they cannot assume canted positions which would tend to bind on the respective stirrups and prevent an easy collapsing of the unit.

Referring to Figs. 1 and 2 which show a typical arrangement of concrete construction with which my unit may be employed, the numeral 22 represents the customary form whose profile determines the underside of the beam 23 and slab 24. The unit is placed in the form 22 with the feet 13 resting upon the bottom of the form, after which the customary reinforcing bars 25 and 26 which resist the horizontal and diagonal tension stresses in the beam may be placed within the unit to rest upon the horizontal portions 14 and 15 of the several stirrups. In this connection, it may be pointed out that one advantage in the employment of the sleeve 16 is the prevention of the dropping of the spacing bar 17 downwardly to such an extent as to interfere with the proper positioning of the bars 25 and 26. Also, it may be noted that the upper spacing bar 20 functions very efficiently as a support for the cross-reinforcing bars 27 which extend through the slab 24, as shown in Fig. 1.

The modification shown in Figs. 7 and 8 differs from the type above described only in the means which is utilized to support the spacing bars of the unit. In the present instance it is contemplated that short channel lengths 28 may be welded or otherwise secured to the end stirrups of the unit in such relation to each other as will secure a positioning of the spacing bars which is comparable to that shown in Figs. 3 and 4. In Fig. 9 is illustrated still another means of supporting the spacing bars and this arrangement takes the form of laterally disposed bends 29 which are formed directly in the limbs of the stirrups in appropriate locations with respect to each other.

While I have shown one set of elements and combinations thereof for effectuating my improved structural unit, it will be understood that the same is intended for purpose of illustration only and in no wise to restrict my device to the exact forms and arrangements shown, for many changes may be made therein without departing from the spirit of my invention.

I claim:

1. A collapsible structural unit comprising a plurality of reinforcing members, means extending the length of the unit and having integrally formed devices for substantially 50 swivelly engaging with said members for maintaining the same in a definite spaced relation, and means for holding said first named means in definite positions endwise of said members.
- 10 2. A collapsible structural unit comprising a plurality of reinforcing members, means extending the length of the unit and having integrally formed devices for substantially 55 swivelly engaging with said members for maintaining the same in a definite spaced relation, and means loosely mounted on said members for holding said first named means in definite positions endwise of said members.
- 15 3. A collapsible structural unit comprising a plurality of upright stirrups, longitudinal bars having tab-like formations bendable around said stirrups for supporting the same in spaced relation, and means for holding 60 said bars in definite positions endwise of said stirrups.
- 20 4. A collapsible structural unit comprising a plurality of upright stirrups, longitudinal bars having tab-like formations bendable around said stirrups for supporting the same in spaced relation, and detachable means for holding 65 said bars in definite positions endwise of said stirrups.
- 25 5. A collapsible structural unit comprising a plurality of upright stirrups, longitudinal bars loosely connected to said stirrups for supporting the same in spaced relation, and sleeves loosely mounted on the end stirrups of the unit for holding said bars in definite 70 positions endwise of said stirrups.
- 30 6. A collapsible structural unit comprising a plurality of upright stirrups, longitudinal bars loosely connected to said stirrups for supporting the same in spaced relation, the end stirrups of the unit having downwardly 75 projecting portions for supporting the unit on the bottom of a form, and sleeves loosely mounted on said end stirrups for holding said bars in definite 80 positions endwise of said stirrups.
- 35 7. A collapsible structural unit comprising a plurality of upright stirrups, longitudinal bars having integral tabs cut out of the body thereof and bendable around the 85 vertical limbs of said stirrups to substantially 90 swivelly engage therewith and maintain the same in a definite spaced relation, and means for holding said bars in definite positions endwise of said stirrups.
- 40 8. A collapsible structural unit comprising a plurality of upright stirrups, channel bars having integral tabs cut out of the webs thereof and bendable around the vertical 95 limbs of said stirrups to maintain the same in a definite spaced relation, and means for holding said longitudinal bars in definite positions endwise of said stirrups.
- 45 9. A collapsible structural unit comprising a plurality of upright stirrups, longitudinal bars having integral tabs cut out of the body thereof and bendable around the vertical limbs of said stirrups to maintain the same in a definite spaced relation, and sleeves loosely mounted on the end stirrups of the unit for holding said bars in definite 100 positions endwise of said stirrups.
- 50 10. A collapsible structural unit comprising a plurality of upright stirrups, channel bars having integral tabs cut out of the webs thereof and bendable around the vertical 105 limbs of said stirrups to maintain the same in a definite spaced relation, and sleeves loosely mounted on the end stirrups of the unit for holding said bars in definite positions endwise of said stirrups.
- 55 11. A collapsible structural unit comprising a plurality of upright stirrups, longitudinal bars having tab-like formations bendable around the vertical limbs of said stirrups to maintain the same in a definite spaced relation, the end stirrups of the unit having downwardly projecting portions for supporting the unit on the bottom of a form, and means for holding said bars in definite 110 positions endwise of said stirrups.
- 60 12. A collapsible structural unit comprising a plurality of upright stirrups, longitudinal bars having tab-like formations bendable around the vertical limbs of said stirrups to maintain the same in a definite spaced relation, the end stirrups of the unit extending below the lower ends of the remaining stirrups and each having a reverse bend for supporting the unit on the bottom of a form, and means for holding said bars in definite 115 positions endwise of said stirrups.
- 65 13. A collapsible structural unit comprising a plurality of upright stirrups, longitudinal bars loosely connected to said stirrups for supporting the same in spaced relation, the end stirrups of the unit extending below the lower ends of the remaining stirrups and each having a reverse bend to provide feet for supporting the unit on the bottom of a form, and sleeves loosely mounted on said end stirrups for holding said bars in definite 120 positions endwise of said stirrups.
- 70 14. A collapsible structural unit comprising a pair of skeleton sides adapted for relative shifting endwise of the unit, each side being composed of a plurality of spaced bars, means connecting the bars across the width of the unit, longitudinal bars having integrally formed devices substantially swivelly 125 engaging with said spaced bars for maintaining the same in a definite spaced relation, and means for holding said longitudinal bars in definite positions endwise of said sides.
- 75 15. A collapsible structural unit comprising 130

ing a pair of skeleton sides adapted for relative shifting endwise of the unit, each side being composed of a plurality of spaced bars, means connecting the bars across the width of the unit, longitudinal bars having integral tabs cut out of the body thereof and bendable around said spaced bars to maintain the same in a definite spaced relation, and means for holding said longitudinal bars in definite positions endwise of said sides.

In testimony whereof, I have subscribed my name.

CHESTER J. O'BRIEN.
